UNITED STATES PATENT OFFICE

ENOCH GEORGE, JR., OF PITTSBURGH, PENNSYLVANIA, ASSIGNOR TO THE McCONWAY & TORLEY COMPANY, OF PITTSBURGH, PENNSYLVANIA, A CORPORATION OF PENNSYLVANIA

DRAFT APPLIANCE FOR RAILWAY CARS

Application filed December 14, 1926. Serial No. 154,737.

My invention relates to draft appliances for railway cars and particularly to those which are primarily designed to permit the coupler to have an extended pivotal or lateral swinging movement when the car to which the device is applied passes around a curve. The primary object of the invention is to provide a draft appliance of the character indicated which is of simple and compact form, is durable and efficient in service, which may be readily assembled, and which is well adapted for application to light passenger cars.

The principal feature of the invention, generally stated, consists in constructing the draft appliance with a draft yoke to the forward end of which a car coupler is pivotally attached by means of a tail pin, the yoke being provided at its forward end with vertically spaced perforated lugs for receiving the tail pin, and having a coupler supporting extension which projects forwardly from the bottom tail pin lug so as to support the coupler in all working positions of the latter, means being provided on the yoke for limiting the pivotal movement of the coupler with respect thereto, and the yoke being operatively associated with a device for cushioning draft and buffing forces.

A further feature of the invention consists in forming the draft yoke with vertically spaced arms for receiving a draft and buffing cushioning device, and in fashioning the forward end of the yoke with vertically spaced perforated lugs adapted to receive a tail pin forming a coupler connection, the lugs being integrally connected at their rear ends by a tie bar which serves to connect the forward ends of the yoke arms, and a coupler supporting extension being integrally united to the bottom tail pin lug and projecting forwardly therefrom so as to support the coupler in all its working positions.

In the drawings illustrating a preferred embodiment of the invention,—

Figure 1 is a plan view of a draft appliance, showing its relation to the draft sills of a car.

Figure 2 is a view, partly in vertical section

and partly in side elevation, of the construction shown in Fig. 1.

In the drawings 1 indicates the sills of the car with which the draft appliance is associated. For the purpose of illustration, but without intent to limit the draft appliance to use in connection therewith, front follower stops 2 and rear follower stops 3 of a well known type are shown as riveted to the sills 1 in spaced relation so as to cooperate respectively with the front follower 4 and rear follower 5 of the cushioning device for resisting draft and buffing forces. Between the followers a spring unit 6, consisting of one or more springs as desired, is interposed in the usual manner. The inner face of each of the followers may advantageously be provided with a plurality of lugs or projections 7 which are of arcuate cylindrical form and are spaced from each other so as to embrace the draft spring and hold it in position. These lugs may be of sufficient length to serve as stops for limiting the compression of the springs between the followers 4 and 5. Employing spring centering lugs 7 positioned outside of the spring unit instead of employing central or axially disposed lugs or studs for that purpose, is advantageous in that it permits of the use of any combination of springs with a given outside diameter.

The draft yoke 8 is preferably formed as an integral casting provided toward its rear end with vertically spaced arms 9 between which the followers 4 and 5 and the spring unit 6 are received. At its forward end it is fashioned with vertically spaced perforated lugs 10 and 11, respectively, between which the rear end or butt of the stem of the car coupler 12 is received. The coupler is pivotally connected to the stem by means of a tail pin 13 which may advantageously be inserted from below. Where, as is the case illustrated in the drawings, the pivotal connection between the coupler and yoke is such that the tail pin 13 is only in double shear, the yoke 8 is preferably formed with a vertically extending tie bar portion 14 which unites the tail pin lugs 10 and 11 at their rear ends and also serves to connect the yoke arms 9 at their forward ends. The tie bar may be conveniently cored

from the rear and its forward face 15 is cylindrically curved to form a buffering bearing for the correspondingly curved rear end 16 of the shank of the coupler 12.

5 Projecting forwardly from the bottom tail pin lug 11 and integrally united thereto is a coupler supporting extension 17 which widens forwardly in fan shape or flaring form so as to provide an efficient support for 10 the coupler in all working positions of the latter. As shown in the drawings, the extension 17 may advantageously be formed with a centrally disposed vertical stiffening web 18 and a lower flange 19, the latter being supported by a carrier plate 20 secured to the sills 1. In advance of the tail pin 13 and on opposite sides thereof, the coupler supporting shelf or extension is integrally provided with upwardly extending projections 21 15 which limit the extent of lateral swinging movement of the coupler with respect to the yoke. The draft appliance may be conveniently supported at its rear end by a carrier plate 22 having down turned flanges which 20 are bolted or otherwise secured to the sills 1. 25

I claim:

1. A railway draft appliance involving a draft yoke, a coupler, and a tail pin for pivotally connecting the yoke and coupler, said 30 yoke being adapted to receive a device for cushioning draft and buffering forces, and being bifurcated at its forward end to provide vertically spaced upper and lower perforated lugs for receiving the tail pin, and having 35 a coupler supporting extension projecting forwardly from the bottom tail pin lug, and extending laterally in opposite directions beyond the upper perforated lug, said extension being adapted to form a support for the 40 coupler when the latter swings with respect to the yoke, and said yoke being provided with means for limiting the pivotal movement of the coupler.

2. A railway draft appliance involving in 45 combination, a draft yoke, a coupler, having a stem, a tail pin for pivotally connecting the yoke and coupler, the yoke being provided with spaced arms for receiving a cushioning device between them, and being bifurcated at 50 its forward end to provide vertically spaced perforated lugs for receiving said tail pin, and having a tie bar integrally connecting the lugs at their rear ends and connecting said arms at their forward ends, and being provided 55 with a coupler supporting extension projecting forwardly from the bottom tail pin lug, said extension affording a bearing surface adapted to engage said stem to support the coupler in all working positions of 60 the latter, and a coupler carrier supportingly engaging said extension in advance of said tail pin.

In testimony whereof I affix my signature.
